UNITED STATES PATENT OFFICE

159,332

ELECTROSURGICAL CABINET

Godfrey P. Goode, Park Hills, Ky., assignor to The
Liebel-Flarsheim Company, Cincinnati, Ohio, a
company of Ohio

Application January 15, 1949, Serial No. 253

Term of patent 14 years

(Cl. D83—1)

To all whom it may concern:

Be it known that I, Godfrey P. Goode, a citizen
of the United States, residing at Park Hills, in
the county of Kenton and State of Kentucky,
have invented a new, original, and ornamental
Design for an Electrosurgical Cabinet, of which
the following is a specification, reference being
had to the accompanying drawing, forming a
part thereof.

The figure is a perspective view of the electro-
surgical cabinet showing my new design. The
two sides of the cabinet are substantially the
same and the rear of the cabinet is plain.

I claim:

The ornamental design for an electrosurgical
cabinet, substantially as shown and described.
GODFREY P. GOODE.
